(57) **CLAIM**

The ornamental design for a beverage center as shown and described.

DESCRIPTION

FIG. 1 is a perspective view of a beverage center showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a perspective view thereof showing an alternative position for the design.

The even spaced broken lines in the drawing depict portions of the beverage center that form no part of the claimed design. The dash-dot broken lines in the drawings define the bounds of the claimed design and form no part thereof.
